WRINGER

Walter L. Kauffman, II, Erie, Pa., assignor to
 Lovell Manufacturing Company, Erie, Pa., a
 corporation of Pennsylvania

Application February 6, 1936, Serial No. 62,605

3 Claims. (Cl. 68—262)

Wringers, as at present made, ordinarily provide a pair of wringer rolls which are subjected to yielding pressure through a spring. Means are usually provided for varying the pressure of the 5 spring.

The present invention is designed to improve the pressure adjusting means by providing devices for indicating the pressure adjustment so that the operator without trial may provide the 10 proper adjustment for the type of clothes which are being passed through the wringer. Other features and details of the invention will appear from the specification and claims.

A preferred embodiment of the invention is illustrated in the accompanying drawing, as follows:

Fig. 1 shows a side elevation of a wringer embodying the invention, the illustration being partly in section to better show construction.

Fig. 2 shows an enlarged view of the operating screw and handle.

Fig. 3 shows a plan view of the screw and a part of the handle detached.

1 marks the base of the frame, 2—2 the side 25 stiles of the wringer, and 3 the top bar. The top bar is secured in place at one end by the interlocking shoulders 2—a and is provided with any desirable safety release 2—b device at the opposite end of the top bar.

30 4 marks the lower wringer roll; 5 the upper wringer roll; 6 the drive shaft for the lower roll; 7 the shaft for the upper roll; 8 the bottom bearing block, one being arranged in each stile; 9 a support for the bearing block 8 arranged in the 35 stiles; 10 the upper bearing block, one being provided for each end of the shaft 7, and being slid- 40 ingly mounted in the side stiles.

A pressure spring 11 extends across the wringer and rests on the upper bearing block. An adjusting screw 12 extends through a nut 13 secured in the top bar. The lower end of the screw has a swivel connection 14 with the spring 11, this swivel connection being provided with a clip 15 which is secured to the spring.

45 All of the parts so far described are or may be of standard construction.

A cross pin 16 extends through the upper portion of the screw and operates in a slot 17, in projection 17a on the base 18 of a handle 19, the 50 parts 18 and 19 being locked together. The handle 19 has a perforation 20 through which the upper end of the screw extends. The upper por-

tion of the screw has the index markings 21, 22 and 23, these markings as shown being "high, med. and low".

When the screw is adjusted downwardly to adjust the spring for the highest pressure, the "high" marking only is exposed. As the screw is retracted to indicate the marking "med." indicating a medium pressure, becomes exposed, and as the screw is further released the index marking "low" is exposed, indicating the lowest operating pressure. Thus the operator is advised of the working pressure to which the wringer is adjusted without any testing with clothes or preliminary operating. Concealing parts of the index leading to the index exposed more definitely 15 fixes the point of index reading and thus simplifies the structure.

What I claim as new is:

1. In a wringer, the combination of a frame; rolls mounted in the frame; means exerting yielding pressure on the rolls; a screw adjusting the means; an operating nut for the screw, the screw extending through the nut and said screw being provided with a handle, and said handle being independent of the axial movement of the screw; and an index indicating the degree of adjustment of the means through the action of the screw, said screw having the index scale thereon exposed through the projection of the screw 20 through the handle.

2. In a wringer, the combination of a frame; rolls mounted on the frame; means exerting yielding pressure on the rolls; an adjusting mechanism for the means comprising a rotative and axially moving screw; and an operating handle 25 for the screw, said handle being independent of any axial movement of the screw and the screw extending through the handle, the projection of the screw through the handle varying with the adjustment of the screw on the pressure means. 30

3. In a wringer, the combination of a frame; rolls mounted on the frame; means exerting yielding pressure on the rolls; and an adjusting mechanism for the means comprising as members a rotative and axially moving screw and an 35 operating handle on the screw, said handle turning with the screw and one of the members being axially stationary and an index on one of the members indicating the relation of the screw and handle and through such relation indicating the 40 degree of adjustment of the means. 45

WALTER L. KAUFFMAN, II.
